UNITED STATES PATENT OFFICE.

WILLIAM A. CAHILL, OF SYRACUSE, NEW YORK:

CARBURETER.

1,078,413.

Specification of Letters Patent. Patented Nov. 11, 1913.

Application filed August 12, 1908. Serial No. 448,155.

To all whom it may concern:

Be it known that I, WILLIAM A. CAHILL, a citizen of the United States, and resident of Syracuse, in the county of Onondaga, in the State of New York, have invented new and useful Improvements in Carbureters, of which the following, taken in connection with the accompanying drawings, is a full, clear, and exact description.

10 This invention relates to carbureters of explosive-engines, and has for its main object the provision of a carbureter whose action will be entirely controlled by the suction of the engine-piston so as to properly 15 proportion and regulate the intake of air and liquid, and which will deliver the mixture to the engine in a thoroughly vaporized condition, and at the same time will permit of positive and convenient adjustment of 20 the liquid-inlet means while the engine is running at any speed so as to increase or decrease the feed of liquid as conditions may require, and whereby the same relative proportions of the air and liquid will 25 be maintained in the mixture regardless of the quantities taken into the carbureter, and furthermore will permit the supply of liquid to be completely cut off while the 30 engine is running and thereby allow the piston to draw the air into the cylinder for the purpose of cooling the cylinder and other parts, in instances where a vehicle is descending a grade, or traveling under momentum.

35 Another object of the present invention is to dispense with the use of a float-valve usually employed for controlling the feed of gasoline or other liquid, and thus produce a construction which will be more efficient and 40 reliable in its action.

Other objects of the invention will be apparent from the novel arrangement and combination of the component parts of the carbureter hereinafter fully described and set 45 forth in the claims.

In the accompanying drawings Figure 1 is a side elevation of the carbureter constructed in accordance with my invention; Fig. 2 is a vertical sectional view of the same; Figs. 3, 4 and 5 are transverse sections taken on the dotted lines —W—W—, —X—X— and —Y—Y— respectively in Fig. 2; Fig. 6 is a detached plan view of the filter through which the gasoline or 55 other liquid passes; Fig. 7 is a like view

with the strainer removed; Fig. 8 is an enlarged detail side view of the upper portion of the carbureter, showing more clearly the mechanism which actuates the liquid-inlet valve, and also showing the manually operated devices for adjusting the links of said valve-actuating mechanism; Fig. 9 is a vertical sectional view on the dotted line —Z—Z— in Fig. 8; and, Fig. 10 is a detail view of the attachment of the tubular air-valve to the rods which form part of the mechanism of the liquid-inlet valve.

Referring to the drawings like numerals of reference indicate like parts.

—1— denotes the usual intake-pipe of an explosive-engine to which the carbureter is applied. My improved carbureter comprises an upright cylindrical casing —2— which has substantially a uniform internal diameter throughout and forms a large and direct air-passage as indicated at —3— and may be connected to the intake-pipe in any convenient manner. In the present instance the pipe and casing are shown detachably united by means of screws —4— passing through external peripheral flanges —5—6— formed respectively on the upper end of the casing and a suitable coupling —6— screwed into the pipe as more clearly shown in Fig. 2. Said casing is provided with openings —7— constituting air-inlet ports which are opened and closed by a valve —8— consisting of a tube adapted to move telescopically within the said casing, which tube is preferably provided with screws or pins —9— projecting outwardly and traveling in longitudinal slots —10— in the casing. This tubular valve —8— is in its lowermost position when the engine is at rest to close the air-inlet ports —7— and it moves to closing position by gravity and is designed to be lifted by the suction created by the engine-piston to open said ports whereby the air is drawn through the passage.

Disposed centrally and longitudinally within the casing is a small tube —11— which extends upwardly from the inlet-ports —7— partway the length of the casing and is rigidly supported therein, preferably by means of transverse pins —12— as shown in Figs. 2 and 3 of the drawings. Said tube forms the main air-passage, while the space surrounding the tube forms an auxiliary air-passage.

The lower end of the tube —11— is provided with a flaring mouth indicated at —13—. Said mouth is disposed a short distance above the lower edges of the ports —7— and it is fitted to the interior of the tubular valve —8— sufficiently tight to prevent the air from passing between said tube —11— and valve when the latter is lifted to a small degree, whereby the air is drawn through the tube or main passage —11—.

Above the main air-passage is arranged a very small transverse tube —14— constituting a nozzle through which the gasolene or other liquid is fed to the passages jointly. This tube —14— is suitably secured at one end in an inlet-opening —15— in the casing and communicating with a cylindrical liquid-chamber —16— secured to or formed integral with the casing as clearly shown in Fig. 2, the other end of said tube being disposed directly over the central tube —11—.

The lower end of the chamber —16— is provided with an opening —16— through which the liquid enters and above the opening is disposed an automatically closing vertically movable valve —17— which is opened by the air-inlet valve —8— whereby the quantities of air and liquid will always be of the same relative proportions as will be hereinafter more fully explained.

The liquid-valve —17— is preferably of conical shape and is provided with a correspondingly shaped seat —18— formed in the chamber, and to the valve is attached a stem —19— passing through a removable cap —20— on the upper end of the chamber, and between said cap and valve and surrounding the stem is a spiral spring —21— which forces the valve to its seat when the valve is thrown out of connection with its operating mechanism as will be hereinafter more fully explained. I prefer to provide this conical valve —17— with a series of circumferential grooves to produce a succession of frustum-shaped rings in order to reduce its bearing surface and insure a more even wear on said surface and at the same time provide scraping edges for cleaning the valve-seat to prevent clogging.

Any suitable mechanism may be employed for connecting the liquid-inlet valve —17— with the aforesaid air-inlet valve —8— whereby the two valves are opened and closed simultaneously incident to the increase and decrease in suction of the engine. The preferred mechanism comprises a pair of parallel elongated plates —22— disposed above and at opposite sides of the gasolene-chamber —16— and which are designed to lie in substantially horizontal position when the valve —17— is closed and are rigidly connected at their outer ends by a transverse bar —23—. The inner end portions of said plates are provided with tubular hubs —24— constituting bearings in which is mounted a shaft —25— having its ends protruding from the plates.

The valve-stem —19— is provided at its upper end with a suitable box or bearing —25— through which the shaft —25— passes and which is composed of two separable parts to allow the shaft and stem to be readily detached if required. The opening of said box is elongated transversely in relation to the shaft to produce a loose connection between said shaft and stem to allow the plates —22— to be swung vertically to raise and lower the stem as will be hereinafter referred to.

—26— denotes a pair of parallel arms which are arranged at opposite sides of the casing —2— and chamber —16— correspondingly with the plates —22—. The said arms are rigidly connected at one end 75 to the respective ends of the shaft —25— and the free end portions of said arms pass slidingly through pivotal bearings —27— supported by means of screws or pins —28— in bifurcations —29— formed at the upper 80 ends of vertically arranged rods —30— which are rigidly connected at their lower ends to opposite sides of the aforesaid tubular air-valve —8—. These rods move in suitable guides —31— provided on the exterior of the casing —2— and may be attached to the valve —8— in any convenient manner. One means of attachment is shown in Fig. 10 of the drawings.

At opposite sides of the casing —2— are 85 arranged parallel horizontal rods —32— passing under the aforesaid shaft —25— and disposed at right angles thereto. These rods are supported longitudinally movable in suitable guides —33— secured to the casing and each has the end portion adjacent to the shaft provided with an upwardly projecting arm —34—, and said rods extend along the outer sides of the respective plates —22— and between each arm and adjacent 90 plate is disposed a link —35— pivotally connected to the arm by means of a pin —36— whereby the said link is adapted to be shifted toward and from the shaft —25—. Said links are formed with circular seats 95 —37— adapting them to partly embrace the respective tubular shaft-bearings or hubs —24— on the plates when the links are shifted to their innermost positions, for the purpose shortly explained. These links are 100 preferably C-shaped and each is provided at its ends with pins —38— adapted to slide respectively in a pair of parallel longitudinal slots —39— provided in the adjacent plate —22—.

The inner end portion of the upper slot 105 of each plate is curved downwardly adjacent to and concentrically with the aforesaid tubular shaft-bearings —24— as indicated at —38—, and each lower slot is pro- 110

115

120

125

130

vided in its top edge with a recess —39—. These curved portions of the upper slots and recesses of the lower slots accommodate the pins —38— when the links embrace the said bearings incident to the lifting of the plates, the said links being moved to this position to allow the valve —19— to close to cut off the feed of liquid when the air-valve —8— is open for the purpose hereinafter more fully explained.

I prefer to provide the pins —38—38 of the links with rollers —40— to reduce the friction in the slots of the plates as clearly illustrated in Fig. 9.

15 The aforesaid rods —32— are rigidly connected by a transverse bar —41— passing through a longitudinal slot —42— provided in a depending lever —43—, pivotally connected to a bracket —44— suitably fastened to the casing —2—, to the lower end of which lever is connected a rod —45— which actuates the same for adjusting the aforesaid links —35— in relation to the shaft —25—.

It is obvious that the means for actuating the lever —43— may include a hand-lever or other suitable device under control of the operator, and this manually-operated device may be provided with a dial or indicator to enable the person in charge to determine the position of the links. Said parts may be arranged and constructed in various ways, and inasmuch as they do not pertain to the present invention they are not illustrated.

In the air-passage and above the liquid-inlet are disposed a set of screens —46—46^a— composed preferably of very fine wire-netting and placed one over another. It has been found in practice that the best results are obtained by employing two of such screens, the lower one being flat and seated with its marginal portion upon a shoulder —47— provided on the interior of the casing —2— and the upper screen formed cone-shaped and seated upon a spacing-ring —48— which clamps the lower screen to the said shoulder. The marginal portion of said upper screen is clamped between the ring and aforesaid coupling —6^x— as shown in Fig. 2.

To the top of the lower screen is secured a small centrally arranged cone-shaped cap —49— also composed of fine wire-netting. The top of the other screen is also provided with a central cap —50— which preferably has its marginal portion flared. By this construction and arrangement of the screens in the passage leading directly to the intake-pipe —1—, it is evident that draft of air and liquid through said screens will cause them to be intimately mixed and delivered to the engine-cylinder in a thoroughly vaporized condition.

5 The carbureter is connected by means of

a pipe —51— to the usual storing-tank indicated at —52— and supported in any convenient manner and elevated some distance above the chamber —16— so as to provide considerable force of the liquid and thereby obtain a more effectual feed of the liquid to the chamber.

In the liquid-passage between the storing-tank —52— and chamber —16— is provided a filter which insures the production of an absolutely pure mixture, and at the same time the liability of the valve —17— becoming clogged is effectually prevented. This filter comprises preferably a vertically disposed chamber —53— which is suitably connected at one side, near the center of its length, to the pipe —51—. The upper end of the chamber —53— is screw-threaded externally whereby it is secured in a suitable correspondingly threaded coupling —54—, 85 which latter is connected to the lower end of the chamber —16— by screw-threading the parts.

At the inlet of the filter-chamber is provided an upturned spout —55— and adjacent to the spout is disposed a deflector —56— consisting of a vertically arranged elongated plate formed circular in cross-section and placed at one side of the center of the chamber. This deflector may be soldered or otherwise fastened in the chamber.

Above the deflector is provided a screen —57— arranged in inclined position and composed of wire-cloth of very fine mesh. The margin of this wire-cloth is secured between two suitably united rings —58— fastened within a tube —59— supported removably within the chamber —53— and preferably seated in recesses —60— provided in the upper portion of the deflector —56— at its junction with the chamber.

The lower end of the chamber —53— is provided with an opening —61— and formed thereat with a screw-threaded nipple —62— to which is applied a removable cap —63—.

It is obvious that when the gasoline or other liquid is drawn into the chamber —53—, the deflector —56— will direct the liquid against the inclined screen —57— whereby any dirt or other substance that may be contained in the liquid will be prevented from entering the chamber —16— and thus become deposited in the bottom of the chamber —53— from which it can be readily removed by taking off the cap —63—. The said screen can be easily removed for the purpose of cleaning the same by disconnecting the chamber —53— so as to permit the withdrawal of the tube —59— in which the said screen is supported.

To prevent the aforesaid air-valve —8— from fluttering during its change of position, incident to the increase or decrease of suction, I provide a cushioning device consisting preferably of an air dash-pot com-

prising a small cylindrical air-chamber —64— rigidly fastened to and depending centrally from a cap or plug —65— secured removably in the lower end of the casing —2—, the lower end of which air-chamber is closed and provided with a pin-hole —66— for the entrance and escape of the air, and in said chamber is arranged a piston —67— which is connected by a rod —68— to a cap or plug —69— suitably secured in the lower end of the tubular air-valve —8—. Said piston-rod passes through a disk —70— which closes the upper end of the chamber —64—.

15 It is evident that when the valve —8— is lifted the piston —67— will draw air into the chamber —64—, and the air will be confined in said chamber owing to the extremely small opening —66—, and thus the gravitating valve, when relieved to a greater or less degree from the suction action of the engine-piston, will be effectually cushioned and allowed to descend without jar, and fluttering is prevented during upward movement, and 20 furthermore under uniform suction-strokes is maintained stationary.

The cap or plug —65— is provided with ports —71— for the escape of air which might otherwise be entrapped in the casing 30 between said plug and lower end of the valve —8— and offer resistance to the valve when the latter tends to close.

To prevent dust from being drawn into the air-ports —7— I provide a screen —72— 35 consisting of a cage-like structure and composed mainly of fine wire-cloth, and housing the casing —2— for a portion of its length and supported thereon in any convenient manner. This screen is clearly illustrated 40 in Fig. 2 of the drawings and is indicated by dotted lines in Fig. 1.

Having described the construction of my carbureter, I will now proceed to explain its operation in order that the same may be 45 more fully understood. Before starting the engine, the links —35— are set at a predetermined distance from the shaft —25— by the operation of the lever —43— and resultant shifting of the rods —32—, whereby the 50 pivots of the rigidly connected slotted plates are adjusted correspondingly to regulate the movement of said plates so as to cause the valve —17— to be opened to the desired degree by the air-valve —8— as will be shortly 55 more specifically pointed out. It is obvious that by the described connection of the links with the shifting-rods and slotted plates, and the connection of the plates with the vertically movable valve-stem —19—, the 60 said plates are retained in their adjusted positions. When the engine has started, the suction created in the intake-pipe —1— and casing lifts the tubular air-valve —8— to open the ports —7—.

65 By opening the ports —7— to a small

degree, the air is drawn through the central tube or main passage —11— owing to the auxiliary passage —3— being maintained closed by the contact of the flaring mouth —13— with the tubular air-valve. By this movement of the valve the rods —30— impart corresponding movement to the free end portion of the arms —26—.

The pivotal connections of the aforesaid links —35— and their shifting-rods —32— 75 and the engagement of the links with the slotted plates —22— causes the inner ends of the latter to be swung upwardly.

The transverse shaft —25— carried by the plates moves in an approximately vertical path and raises the valve —19— whereby a certain quantity of liquid is permitted to be drawn through the chamber —16— and nozzle —14—. The arrangement of this nozzle in relation to the air-passage —11— 85 and the provision of the screens —46— 48 hereinbefore described causes the air and liquid to be intimately mixed so as to supply the mixture to the engine-cylinder in a thoroughly vaporized condition. As the suction becomes stronger the valve is caused to be lifted to a greater extent to increase the area of the inlet-ports —7— and at the same said valve, through the described mechanism, opens the valve —19— to a greater degree to permit an increased quantity of liquid to be drawn into the air-passage. The continued lifting of the valve —8— carries its lower end above the flaring mouth —13— of the tube —11—, whereby 100 a larger quantity of air is drawn through the auxiliary passage —3—. This increase in the supply of air and liquid obviously produces greater engine-speed. It will be understood however, that this suction action 105 is to be controlled by means of a suitable throttling device (not necessary to be shown) applied to the intake-pipe —1— in the usual and well known manner.

It is evident that by simultaneously actuating the air-inlet valve and liquid-inlet valve, the same relative proportions of air and liquid will be maintained in the mixture regardless of the quantities taken in.

When the operator closes down the 115 throttle-valve, the suction in the intake-pipe will obviously be decreased, whereby the valve —8— will by gravitation move down and thereby reduce the area of the air-inlet ports —7—, and the described connections 120 between the said valve and liquid-valve —19— will cause the latter to be moved simultaneously and correspondingly to reduce the feed of liquid, thus decreasing the supply of mixture to the engine. By this 125 simultaneous and automatic action of the two valves the air and liquid in the mixture are always of the same relative proportions.

If it is found that the proportion of liquid should be increased or decreased to meet 130

changes in weather conditions or for other reasons, the operator can readily adjust the aforesaid links —35— to a greater or less distance from the shaft —25— to correspondingly increase and decrease the leverage of the vertically swinging plates —22—, and thus regulate the action of the valve —19—. This regulation of the valve-action is effected by operating the lever —34— hereinbefore referred to. Under ordinary conditions, the links —35— when once set in such position as to obtain proper results, are not required to be disturbed, except in case it is desired to allow the valve —19— to completely close to cut off the feed of liquid to the air-passage as will be shortly explained. This position of said links can be readily determined by the use of a dial or indicator (not shown) connected to or actuated by a suitable hand-lever or other device arranged to be conveniently operated by the person in charge.

If it is desired to entirely cut off the feed of liquid while the engine is running, the operator moves the hand-lever or other device referred to for throwing the lever —34— outward as indicated by dotted lines in Fig. 8 of the drawings. This movement of the lever and corresponding shifting movement of the rods —32— carries the links —35— inwardly in relation to the casing, whereby said links are caused to embrace the aforesaid tubular hubs or bearings —24— of the shaft —25—. The links 35 are permitted to assume this position by reason of the upper slots of the plates —22— being curved concentrically with the said tubular bearings and the lower slots being provided with recesses as hereinbefore described. By thus positioning the links when the engine is running, the fulcrums of the plates are transferred from the link-pivots —36— to the shaft —25— whereby the links are thrown out of operative connection with the slotted plates to allow the latter to drop to close the valve —19—. This action of the valve is insured by the spiral-spring —21— surrounding the valve-stem and disposed between valve and top of the chamber —16—.

The complete cutting off of the liquid while the engine is running is desirable in instance where the engine is mounted on a vehicle. For example, when the vehicle is descending a grade or traveling under momentum following the cutting out of the ignition means, by allowing the liquid-valve to close as stated, the piston is caused to draw the air into the cylinder and thus effectually cool the engine.

It will be understood that during the cooling action of the carbureter, the throttling-device may be fully opened to allow the cylinder to receive the air to its fullest capacity.

As the engine slows down, it is obvious that the resultant decrease in suction will allow the gravitating air-valve —8— to move down. This movement of the valve will be very gradual owing to the slow escape of air from the chamber —64— of the dash-pot or cushioning device hereinbefore described, however it will be evident that the valve will not completely close until the engine comes to rest. While the vehicle is thus travelling, the operator can control the feed of liquid at will by actuating the lever —34— to effect a few or continued explosions as desired. It is understood that this movement of the lever shifts the aforesaid links away from the shaft —25— so as to transfer the fulcrum of the plates from said shaft back to the pivots —36— of the links, and the engagement of the links with the slots of the plates causes the latter to lift the valve —19—. It is evident that the said links can be set in the same positions they occupied before cutting off the liquid so that the relative proportions of the air and liquid will remain unchanged, this position can be readily determined by the use of the dial or indicator associated with the hand-lever or other operating device as hereinbefore stated.

What I claim is:—

1. In a carbureter of an explosive-engine, the combination of a vertically movable air-inlet valve opened by suction and adapted to close by gravitation, a liquid-inlet valve, mechanism connecting said valves so as to cause the two valves to open and close simultaneously, and manually operated adjusting means connected to the said mechanism whereby the latter causes the liquid-inlet valve to close and allows the air inlet valve to operate independently of the liquid-inlet valve as set forth.

2. In a carbureter, the combination of an upright casing having a direct air-passage provided with an inlet-port, a tubular-valve movable longitudinally in the passage and opened by suction and adapted to close automatically, a liquid-feed connected to the casing, a valve controlling the feed of liquid, mechanism connecting the latter valve with the tubular valve whereby the two valves are adapted to open and close simultaneously, and manually operated adjusting means connected to said mechanism whereby said mechanism allows the air-inlet valve to operate independently of the other valve as set forth.

3. In a carbureter, the combination of an upright casing having a direct air-passage provided with an inlet-port, an automatically closing tubular valve movable longitudinally in the passage and controlled by suction for opening and closing said port, a liquid-inlet nozzle extending into the passage above the air-inlet port, a valve con-

- trolling the feed of liquid through the nozzle, mechanism connecting the liquid-inlet valve to the tubular-valve whereby said valves are adapted to open and close simultaneously, and adjusting means connected to the said mechanism for causing the latter to allow the liquid-inlet valve to close and the air-inlet valve to operate independently of the liquid-inlet valve as set forth. 5
4. In a carbureter, the combination of a casing having a main air-passage and an auxiliary air-passage and provided with a single inlet-port for the two passages, and provided with a liquid-inlet opening, a valve controlled by suction for opening and closing said port, a valve for regulating the feed of liquid through said opening, mechanism connecting the liquid-feed valve to the air-valve, and manually operated adjusting means connected to said mechanism for causing said mechanism to allow the liquid-feed valve to close independently of the air-valve. 10
5. In a carbureter, the combination of an upright casing having main and auxiliary air-passages and provided with one inlet-port for both passages, and provided with a liquid-inlet opening, a vertically movable valve lifted by suction to open the air-inlet port and adapted to drop automatically for closing the port, liquid-supply means communicating with said inlet-opening, a valve for controlling the feed of liquid, mechanism connecting the liquid-feed valve to the air-valve, and manually operated means connected to said mechanism whereby the latter allows the liquid feed valve to close independently of the air-valve as set forth. 15
6. In a carbureter, the combination of a casing having a central main air-passage and an auxiliary air-passage surrounding the main air-passage and provided with an inlet-port therefor, a valve operated by suction for opening the port, and adapted to close by gravity, said passages and valve being arranged so as to cause the air to be drawn entirely through the main passage when the valve opens the port to a small degree and to cause air to be drawn through both passages as the valve continues to open the port, a liquid feed-nozzle having its discharge end arranged directly over the main air-passage, a self-closing valve controlling the feed of liquid, and means actuated by the opening movement of the air-valve for opening said liquid-valve as set forth. 20
7. In a carbureter, the combination of a casing having an air-passage provided with an inlet-port, means controlled by suction for opening and closing said port, a liquid chamber having a suitable source of supply and communicating with the air-passage, a valve in said chamber for controlling the feed of liquid to the passage, mechanism actuated by the suction-controlled means for opening and closing the liquid-valve, and manually operated adjusting means connected to said mechanism and adapting the latter to cause the said liquid-valve to close independently of the suction-controlled means as set forth. 25
8. In a carbureter, the combination of a casing having an air-passage provided with an inlet-port, an automatically closing valve disposed in the passage and adapted to be opened by suction, a liquid-receiving chamber having a suitable source of supply and communicating with the air-passage above the inlet-port, a vertically movable valve controlling the communication between the chamber and passage, mechanism connecting said valves, whereby the quantities of air and liquid drawn into the passage are correspondingly increased and decreased as the suction strengthens and weakens so as to maintain the same relative proportions in the mixture, and manually operated adjusting means connected to said mechanism whereby said mechanism will cause the liquid-valve to close and the air-inlet valve to operate independently of the liquid-inlet valve. 30
9. In a carbureter of an explosive-engine, the combination of a casing having a vertical air-passage provided with an inlet-port, a valve movable longitudinally in said passage for opening and closing the port, said valve being lifted by suction and adapted to drop by gravitation, a chamber at the exterior of the casing having liquid-supply means and communicating with the air-passage above the port, a vertically movable valve in said chamber for controlling the feed of liquid to the passage, mechanism actuated by the air-valve for opening and closing the liquid-valve, and manually operated adjusting means connected to said mechanism whereby the latter will allow the liquid-valve to close independently of the air-valve. 35
10. In a carbureter of an explosive-engine, the combination of a casing having a vertical cylindrical air-passage provided with an inlet-port in its side, a tubular valve in said passage raised by suction to open the port and adapted to be lowered by gravity for closing said port, a liquid-receiving chamber communicating with the air-passage above the air-inlet port, a valve movable vertically in the chamber for controlling the feed of liquid to said passage, mechanism actuated by the air-valve for operating the liquid-valve and including a pivotally mounted member, the pivot of said member being shiftable to permit greater or less movement to the said liquid-valve, and manually-operated means for shifting the said pivot to cause an increased or decreased quantity of liquid to be drawn into the air passage and adapting said 40

liquid valve to close independently of the air-valve as set forth.

11. In a carbureter of an explosive-engine, the combination of a casing having 5 main and auxiliary air-passages and provided with an inlet-port for the passages, a valve operated by suction for opening the port whereby air is first drawn through the main passage and then through both 10 passages, said valve being adapted to automatically close the port incident to the decrease in suction, a liquid-receiving chamber having a suitable source of supply and provided with an exit-opening, a feed-nozzle extending from the opening into the 15 casing and terminating over the main air-passage, a valve in the liquid-chamber for controlling the feed through the nozzle, and mechanism actuated by the air-valve for 20 governing the said liquid-valve as set forth.
12. In a carbureter of an explosive-engine, the combination of a casing having an air-passage and provided with air and liquid-inlets, valves controlling the intake 25 of air and liquid-feed and opened by suction and adapted to close automatically, mechanism connecting the two valves and comprising a pair of vertically swinging longitudinally slotted plates rigidly united, 30 means connecting the plates, normally stationary rods adapted to be shifted along the sides of the plates, links pivotally connected to the rods and engaging the slots of the plates to permit said links to be set a 35 greater or less distance from the valve-connection to increase or decrease the movements of the plate to regulate the acting of said liquid-valve, and means for shifting said rods as set forth.
13. In a carbureter of an explosive-engine, the combination of an air-inlet valve and a liquid-inlet valve controlled by suction, a stem attached to the liquid-inlet valve, mechanism actuating the latter valve 45 comprising a horizontal shaft connected in-

termidiate of its ends to the valve-stem, a pair of rigidly united parallel longitudinally-slotted plates connected to the shaft and having fulcrums shiftable in the slots thereof, means raising and lowering said 50 plates, and manually-operated adjusting means comprising a pair of parallel longitudinally movable rods connected at one end to the fulcrums of the plates for shifting the fulcrums toward and from the aforesaid shaft to increase or decrease the movement of the plates, and a lever for moving the rods as and for the purpose set forth.

14. In a carbureter of an explosive-engine, the combination of an upright cylindrical casing forming an air-passage and provided with a small central longitudinal tube also constituting an air-passage, the lower end of said tube provided with a flaring mouth, said casing being provided with 60 an air-inlet port disposed at said mouth, a tubular valve sliding telescopically within the casing and lifted by suction for opening the port to allow the air to be drawn through both passages and adapted to be 65 lowered by gravity for closing the port, a liquid-receiving chamber having a suitable source of supply, a feed-nozzle leading from the chamber and terminating in the casing directly above the central air-passage, a 70 vertically movable valve in the liquid-chamber for controlling the feed through the nozzle, mechanism actuated by the air-valve for operating the liquid-valve, and means by which said mechanism can be 75 adjusted to regulate the action of the liquid-valve and whereby the latter may be thrown out of operative connection with the air-valve while the air-valve is in open position for the purpose described, and means 80 for closing said liquid-valve as set forth.

WILLIAM A. CAHILL.
